UNITED STATES PATENT OFFICE.

MARWOOD D. VAN AUKEN, OF NEW YORK, N. Y.

ANTISKID AND QUICK-STOP.

1,151,068.

Specification of Letters Patent. Patented Aug. 24, 1915.

Application filed June 23, 1914. Serial No. 846,848.

To all whom it may concern:

Be it known that I, MARWOOD D. VAN AUKEN, a citizen of the United States, residing at New York, in the county of New York and the State of New York, have invented a new and useful Improvement in Antiskids and Quick-Stops, of which the following is a specification.

This invention relates to a device for 10 stopping an automobile, lifting one wheel from the ground, and preventing skidding, said device being carried by the axle and not connected to the wheel, and operated from the driver's seat, the device being normally 15 suspended in an inoperative position and when released dropping into operative position by gravity.

The invention consists broadly in a pivoted shoe suspended on the inside of the 20 wheel, and with means for normally holding the same elevated beneath the vehicle body, the shoe when dropped falling into the path of the wheel which rides into said shoe, and is lifted from the ground, the 25 ground engaging face of the shoe being suitably roughened.

The invention also includes means for suspending the shoe so that when released its fall will be cushioned.

With these objects in view the invention 30 also consists in the novel features of construction hereinafter described, pointed out in the claims, and shown in the accompanying drawings, in which:

Figure 1 is a sectional side view, the inner 35 side of a wheel being shown and a vehicle body being dotted. Fig. 2 is a view looking from the front toward the wheel, parts being broken off, the shoe being in operative position. Fig. 3 is a section on the line 3—3 of 40 Fig. 1. Fig. 4 is a section on the line 4—4 of Fig. 1.

In the drawings 1 represents a foot operated lever which rocks a suitable link 2, 45 which in turn swings a hook lever 3, these parts being pivotally connected by a rod 4.

The hook 3 engages a suitable catch 5 carried by a piston rod 6 which in turn is pivotally connected to a shoe 7. This shoe is 50 preferably in the form of an angled plate pivotally hung on bearing 8 carried by a plate or bracket 9, secured to the cup or otherwise mounted on the rear axle, the exact manner of fastening the bracket or its 55 exact form not being regarded as material.

The plate forming the shoe 7 is laterally angled as at 7^a to receive the wheel tire when dropped into the path of the wheel, whereby displacement of the tire is prevented by use of the shoe. 60

A second piston rod 10 is pivotally connected to a bracket 13 carried by the under-side of the vehicle frame or body 14. The rods 6 and 10 have heads 16 and 17 which work in a cylinder 11, said cylinder being provided with longitudinally arranged air vents 12. A spring 15 serves to return the parts to normal position. 65

The parts are normally suspended as shown in dotted lines in Fig. 1. To operate 70 the foot lever 1 is pushed forwardly thereby rocking the link 2 and through the rod 4 swinging the lever 3 out of engagement with the hook 5, the lever and link being returned to normal position upon release of foot 75 pressure by the spring 15. The hook 5 being released the shoe 7 drops by gravity into the position shown by full lines in the drawings, its fall be regulated by movement of the pistons 16 and 17 and the escape of air 80 through the vents 12, as will be readily understood. The wheel rides upon the portion 7^a of the shoe and is lifted from the ground. The shoe is knurled or roughened on the underside to prevent skidding. 85

From the drawings and the above description the use and advantages of the device will be obvious. It can be applied to any make of automobile, and minor changes of construction can be made to adapt the device 90 to vehicles of different constructions without altering any of the essential features of the invention.

The shoe is released by backing the automobile and then raising it manually to normal position. 95

What I claim is:

1. The combination with an automobile, of a pivoted shoe curved transversely to receive an automobile wheel, a cylinder supported from the automobile frame, having an air vent therein, a piston rod working in said cylinder and pivotally connected to said shoe, a hook carried by the rod, means carried by the frame for engaging said hook 10 and holding said shoe in elevated position, and means for releasing the said hook from its engaging means. 105

2. The combination with an automobile, of a pivoted shoe adapted when in engage- 110

ment with the ground to receive an automobile wheel tire, a rod pivoted to said shoe and having a head thereon, a second headed rod, a cylinder in which the heads of said rods work, said cylinder having air vents therein, a hook carried by the first mentioned rod, a second hook carried by the au-

tomobile frame for engaging the rod hook, and means operable from the automobile seat for disengaging said hooks.

MARWOOD D. VAN AUKEN.
